(57) CLAIM

We claim the ornamental design for a liquid cooling pump set set, as shown and described.

DESCRIPTION

FIG. 1 is a perspective view of a liquid cooling pump set showing our new design;

FIG. 2 is a front view of the liquid cooling pump set of FIG. 1;

FIG. 3 is a rear view of the liquid cooling pump set of FIG. 1;

FIG. 4 is a left side view of the liquid cooling pump set of FIG. 1;

FIG. 5 is a right side view of the liquid cooling pump set of FIG. 1;

FIG. 6 is a top view of the liquid cooling pump set of FIG. 1; and,

FIG. 7 is a bottom view of the liquid cooling pump set of FIG. 1.
